CREEPING TRACTION

Mitchell L. Fykse, South Milwaukee, and Harry E. Bauer, Milwaukee, Wis., assignors to Bucyrus-Erie Company, South Milwaukee, Wis., a corporation of Delaware

Application September 11, 1930
Serial No. 481,164

6 Claims. (Cl. 212—145)

Our invention relates to new and useful improvements in creeping traction.

Our principal object is to provide a creeping traction mounting for excavators, cranes and the like, which shall possess in operation a base wider than railroad clearance, and yet may easily be reduced in width to within railroad clearance for shipment.

It has been proposed in the past to solve this problem by building the traction-device so that its wheels will fall just within railroad clearance, and its treads will extend beyond railroad clearance. Then, shipping, the treads are removed, and the wheels are run onto special rails on a flat car.

But a mere extension of the treads beyond the wheels, while keeping the wheels within railroad clearance, does not sufficiently extend the stability.

Accordingly it is our object to extend the effective stability base of the machine still further.

Further objects are to develop a novel traction link, and to develop a novel wheel arrangement.

In addition to our principal object, we have worked out a number of novel and useful details, which will be readily evident as the description progresses.

Our invention consists in the novel parts, and in the combinations and arrangements thereof, which are defined in the appended claims; and of which one embodiment is exemplified in the accompanying drawings, which are hereinafter particularly described and explained.

Throughout the description, the same reference number is applied to the same member or to similar members.

Referring to the drawings, it will be seen that: Figure 1 shows in outline an excavator, as

loaded according to our method, for transportation.

Figure 2 is a plan view, taken from below, showing details of our creeping traction mechanism.

Figure 3 is a vertical section, taken along the line 3—3 of Figure 2, showing our auxiliary roller and its associated shaft, with the tread belt disposed around it.

Beginning at Figure 1, it will be seen that 10 is a railroad track, upon which are stationed a flat car, A, intended for the excavator proper, and a second flat car, B, upon which the accessories are to be placed.

Car A has securely fastened to its upper surface a pair of rails, 11, spaced apart as herein-after determined, upon which the excavator 12 is

to be loaded in the manner hereinafter described.

We have also provided a ramp 13, with rails 14 securely fastened to its upper surface, the rails being spaced apart the same distance as the rails 11 on car A, so that, when the ramp is positioned, the upper end of rails 14 may abut the ends of rails 11. In the preferred form, the ramp has a steeper slope at the ground engaging end, the slope at the car engaging end being small enough that the excavator 12 may remain thereon without sliding.

The excavator consists of the usual base 15, with creeping traction members, of which Figure 1 shows only the side-frame 16, the tumblers 17 and 18 and the rollers 19, 20, 21; inasmuch as the tread-belt (not shown in Figure 1) is to be removed before the excavator is placed in the position shown.

The upper portion 22 of the excavator 12, is capable of being revolved about the pintle-center 75 P on the base 15, and carries a deck 23, for the placing of the usual actuating machinery, such as the winch-drum 24, for actuating the hoist cable (not shown) which passes to a sheave at the point of the boom 25. The boom is shown 80 as already detached, and laid upon the car, B.

The only other appliance carried by the deck with which our invention is concerned is the A-frame 26, which is made collapsible in order to diminish the head-room required in shipping. Member 27 of the A-frame is pivoted at 28 to the support of the winch-drum 24, and to its other end 29 is pivoted the member 30. The lower end of 30 is fastened to a yoke-shaped member 31, by a removable pin 32. The A-frame is collapsed by removing pin 32, and disposing the members as shown by the dotted lines, the member 27 being laid in the yoke of member 31.

Turning now to Figure 2, we have shown the 95 side frames 16 as carrying on shafts the driving tumbler 17, idler tumbler 18, and rollers 19, 20, 21. Power is conveyed from the engine (not shown) to the driving tumbler 17, by a succession of gears, 33, 34, 35.

The driving tumbler 17 is provided with laterally projecting lugs 36, for driving engagement with the tread belt links, 37.

Each tread-belt link 37 is provided with a relatively broad tread, or ground-engaging, surface, 105 38. Its upper surface has, centrally disposed, a relatively narrow, flat, wheel-engaging surface, 39. At each side of this surface 39 is an up-standing flange 40, having its central part cut away for the extrusion of dirt, these flanges being 110

for driving cooperation with the laterally projecting lugs 36 on the driving tumbler 17. The lugs 36 on the driving tumbler 17 and the flanges 40 are relatively so placed that, when the tread-belt curves about the tumbler, lugs 36 fall between the flanges 40 of successive links. The above-enumerated features of the tread-belt links are more particularly described in copending application, Serial No. 299,071 of Snyder. In addition to these features, our link has, on each side of the central wheel-engaging surface, and spaced apart therefrom, a flat, auxiliary runway 41, whose purpose will be later explained.

The load-supporting rollers, 19, 20, 21, and 15 the idling tumbler 18, are disposed to run over the same narrow wheel-engaging channel 39 in which the driving tumbler runs.

As shown on Figures 2 and 3, the lower, inner edge of each side frame 16, has along its length 20 a heavy flange 42, which is provided, on its upper surface, with a groove 43, into which a downwardly projecting flange 44 on the base 15, is stepped. A groove 45 extends along the lower surface of the flange 42. At the ends of the side-frames 16, the grooves 45 are somewhat curved vertically upward, to allow of easier placing 25 on the rails of the ramp.

The distance between the grooves 45 of the two side-frames 16 determines the distance between the rails 11 on car A, and the same distance between the rails 14 of the ramp; so that, when the excavator is set upon the ramp or upon car A, the grooves 45 will fit over the rails 11 or 14 respectively.

Turning now to Figure 3, it is seen that the central roller 20, is mounted on a hollow shaft 46, which shaft is secured by bolt 47 to the side frame 16. The roller 20 is rotatably secured on the outer end of the shaft 46, by a ring-shaped 40 retaining nut 48.

Removably inserted in hollow shaft 46, is an auxiliary roller shaft 49, which is secured to shaft 46 by a bolt 50, and which projects beyond the retaining nut 48 a distance sufficient to furnish a bearing for an auxiliary roller 51, rotatably mounted thereon and adapted to run on the auxiliary wheel-engaging surface 41 of the links 37. Auxiliary roller 51 is rotatably secured on auxiliary shaft 49 by a retaining nut 52.

It is to be noted that this auxiliary roller 51 serves as a jack-arm and thus greatly increases the lateral stability of the machine over that of the narrower machines which heretofore have been limited by the narrowness of railroad clearances. It is to be further noted that this auxiliary roller 51 is located exactly opposite the pintle-center P, where the radial distance to the roller 20 is less, and hence more critical, than the radial distance to the rollers 17, 18, 19 and 21.

Roller 51 thus serves merely as a jack-arm at this point. The absence of auxiliary rollers opposite rollers 17, 18, 19 and 21, leaves the track still laterally flexible at these points, and the absence of any auxiliary roller between roller 20 and the main base 15 leaves the track laterally flexible in one direction at this point; thus sacrificing the very minimum of lateral flexibility for the sake of attaining an increased lateral stability over that permitted by railroad clearances.

Our invention contemplates the possibility of making an excavator of such large size that, when completely assembled, it will not be within railroad clearances; yet, when only a very few of its members are dismounted, leaving the excavator 75 still capable of locomotion under its own power,

the machine can then be shipped by rail, without further disassembling.

For shipping purposes, we propose to remove the tread-belt 37, retaining nut 52, auxiliary roller 51, bolt 50, auxiliary roller shaft 49, the dipper and handle (not shown), and the boom 25. When pin 32 is withdrawn from the yoke-shaped member 31 of the A-frame, and the A-frame is collapsed into the position shown in Figure 1 by dotted lines, the machine is ready for shipment.

The method of loading the excavator onto flat cars, and the exclusive features of our excavator which permit such loading, will be covered in a divisional of this application.

Having now described and illustrated one form of our invention, we wish it to be understood that our invention is not to be limited to the specific form or arrangement of parts hereinbefore described, except in so far as such limitations are specified in the appended claims.

We claim:

1. In an excavator, or the like, mounted on creeping traction, the combination of: a base; an upper portion, capable of revolving about a pintle-center on the base; and a creeping traction unit on each side of the base, supporting it; each such unit comprising: a series of connected links, each link having a relatively broad tread surface, a narrow flat centrally-disposed wheel-engaging surface, two rows of upstanding wheel-guiding flanges, one row thereof being on each side of said wheel-engaging surface, and a flat auxiliary wheel-engaging surface disposed to one side of, and further from the pintle-center than, the normal wheel-engaging surface; a driving tumbler, disposed between said flanges, and having lateral lugs disposed for driving engagement between the flanges of successive links; load-supporting wheels, disposed between said flanges; and a removable auxiliary load-supporting jack-arm wheel and associated shaft, said wheel being located adjacent a line drawn laterally through the pintle-center, and being disposed to run on the auxiliary wheel-engaging surfaces; all the parts of said excavator, or the like, being within railroad clearance, except the tread belt and the auxiliary wheel and its associated shaft, which extend beyond railroad clearance.

2. In an excavator, or the like, mounted on creeping traction, the combination of: a base; an upper portion, capable of revolving about a pintle-center on the base; and a creeping traction unit on each side of the base, supporting it; each such unit comprising: a series of connected links, each link having a narrow flat centrally-disposed wheel-engaging surface, and a flat auxiliary wheel-engaging surface disposed to one side of, and further from the pintle-center than, the normal wheel-engaging surface; a driving tumbler and load-supporting wheels, all disposed to run on said central surfaces; and a removable auxiliary load-supporting jack-arm wheel and associated shaft, said wheel being located adjacent a line drawn laterally through the pintle-center, and being disposed to run on the auxiliary wheel-engaging surfaces; all the parts of said excavator, or the like, being within a railroad clearance, except the tread belt and the auxiliary wheel and its associated shaft, which extend beyond railroad clearance.

3. In an excavator, or the like, mounted on creeping traction, the combination of: a base; an upper portion, capable of revolving about a pintle-center on the base; and a creeping trac-

6. In an excavator, or the like, mounted on creeping traction, the combination of: a base; an upper portion, capable of revolving about a pintle-center on the base; and a creeping traction unit on each side of the base, supporting it; each such unit comprising: a series of connected links, each link having a relatively broad tread surface, a narrow flat centrally-disposed wheel-engaging surface, two rows of upstanding wheel-guiding flanges, one row thereof being on each side of said wheel-engaging surface, and a flat auxiliary wheel-engaging surface disposed to one side of, and further from the pintle-center than, the normal wheel-engaging surface; a driving tumbler and load-supporting wheels, all disposed to run on said central surfaces; and a removable auxiliary load-supporting jack-arm wheel and associated shaft, said wheel being located adjacent a line drawn laterally through the pintle-center, and being disposed to run on the auxiliary wheel-engaging surfaces.

7. In an excavator, or the like, mounted on creeping traction, the combination of: a base; an upper portion, capable of revolving about a pintle-center on the base; and a creeping traction unit on each side of the base, supporting it; each such unit comprising: a series of connected links, each link having a relatively broad tread surface, a narrow flat centrally-disposed wheel-engaging surface, two rows of upstanding wheel-guiding flanges, one row thereof being on each side of said wheel-engaging surface, and a flat auxiliary wheel-engaging surface disposed to one side of, and further from the pintle-center than, the normal wheel-engaging surface; a driving tumbler, disposed between said flanges, and having lateral lugs disposed for driving engagement between the flanges of successive links; load-supporting wheels, disposed between said flanges; and a removable auxiliary load-supporting jack-arm wheel and associated shaft, said wheel being located adjacent a line drawn laterally through the pintle-center, and being disposed to run on the auxiliary wheel-engaging surfaces; all the parts of said excavator, or the like, being within railroad clearance, except the tread belt and the auxiliary wheel and its associated shaft, which extend beyond railroad clearance; the maximum of lateral link flexibility being maintained, consistent with jack-arm effect where needed, by having no auxiliary load supporting wheels remote from the lateral line above referred to.

MITCHELL L. FYKSE.
HARRY E. BAUER.
